UNITED STATES PATENT OFFICE.

WILLIAM R. DOUGHTY, OF WAYLAND, NEW YORK.

RAILROAD-TIE.

1,242,782.

Specification of Letters Patent.

Patented Oct. 9, 1917.

Application filed July 9, 1917. Serial No. 179,485.

To all whom it may concern:

Be it known that I, WILLIAM R. DOUGHTY, a citizen of the United States, residing at Wayland, in the county of Steuben and 5 State of New York, have invented new and useful Improvements in Railroad-Ties, of which the following is a specification.

This invention relates to improvements in metallic ties for railway rails, and has for its 10 primary object to provide means whereby the rails may be quickly and securely locked upon the tie, or readily removed therefrom as occasion requires.

It is a further object of the invention to 15 produce a metallic tie for supporting railway rails, wherein the rails are connected to the tie without the employment of spikes, bolts and analogous securing elements.

A still further object of the invention is 20 to produce a metallic tie having integrally formed therewith, elements designed to engage with one of the sides of the rails which are supported upon the tie, the said tie being further provided with removable rail 25 engaging elements designed to engage with the opposite sides of the tie, the latter rail engaging elements being removable, to permit of the rails being first laid upon the ties and engaged by the first mentioned elements 30 and thereafter engaged by the last mentioned elements, whereby not only to facilitate the laying of the rails, but also the manner of locking the same upon the ties.

Other objects and advantages will present 35 themselves as the nature of the invention is more fully understood, reference being had to the accompanying drawings, in which,

Figure 1 is a perspective view of a tie constructed in accordance with the present invention and illustrating the rails secured 40 thereon.

Fig. 2 is a greatly enlarged central longitudinal sectional view, showing one of the 45 ends of the tie and one of the rails upon the tie.

Fig. 3 is a perspective view of one of the ends of the tie with the locking element removed therefrom.

Fig. 4 is a perspective view of a removable 50 rail engaging element, and

Fig. 5 is a bottom plan view of the same, and

Fig. 6 is a perspective view of the bolt operating member having the removable rail engaging elements. 55

The tie is indicated by the numeral 1, the same being preferably constructed of a substantially rectangular body of metal, the same, upon its upper face, being provided with vertical extensions or lugs 2—2, one 60 being arranged near the end of the tie and the other inward of the opposite end of the tie, both of the said lugs 2 having one of their edges undercut to provide lips 3, and these lips are designed to engage with the 65 base flanges of the rails 4, as clearly illustrated by the drawings.

The tie, at a suitable distance from the referred to lugs 2, is formed with substantially rectangular pockets 5, the walls of the said 70 pockets, nearest the respective lugs 2 being beveled inwardly as at 6, the opposite end walls being vertical but provided with an approximately centrally arranged longitudinally extending slot 7. The opposite side 75 or longitudinal walls provided by the depressions 5 are parallel, and the tie proper is cut parallel to the said side walls and outward thereof forming a horizontally disposed shoulder 8 for each of the said side walls. The pockets 5 provide pockets for the reduced inner portions of the removable rail engaging members 9, the same being in the nature of substantially rectangular block members, each of which having one of 80 its ends formed with an extension provided with a lip 10, the said lip being designed to engage with the edge and overlie the flange of the base of the rail opposite that engaged by the lips 3 of the lugs 2. The ends of the 85 rail engaging members provided with the lips 10 are formed with an oppositely beveled portion or tongue 11, and the said tongues of the respective members are adapted to engage with the beveled end walls of the respective pockets 5. The referred to under 90 face of each of the rail engaging members 9 is of a less width than the body of the said members, forming the body proper with what I will term shoulders 12, and these shoulders are designed to rest upon the shoulders 8 of the pockets 5. The reduced under face of the body is indicated by the character 13 and may, as illustrated in the

100

drawings, comprise two spaced members, one of which forming a portion of the tongue 11 and the other or outer member being in the nature of a housing 14 for the reception of a sliding bolt 15. The bolt has its outer end, from its upper face beveled inwardly as at 16, and the numeral 17 designates a helical spring, having one of its ends received in a depression or socket in the inner member upon the lower face of the rail engaging elements 9, which, for distinction, is indicated by the numeral 18, the opposite end of the said spring surrounding a reduced extension upon the inner end of the bolt 15, and contacting with the said extension and the bolt proper. The bolt, upon its outer surface is provided with a slot 19 communicating with a preferably angularly disposed opening 20, provided in the upper face of each of the rail engaging members 9, and designed to be passed through the opening 20, and engaged in the depression 19 of the bolt is a suitable instrument such as illustrated by the dotted lines illustrated in Fig. 2 of the drawings, the walls of the opening providing a fulcrum for the said instrument, whereby, when the same is swung upon such fulcrum, the bolt may be retracted against the pressure of the spring 17 to bring the end thereof out of the slot 7 in the end walls of the respective pockets 5.

As the lugs 2 are integrally formed with the tie, it will be noted that the laying of the rails will be greatly facilitated, as said rails, when engaging with the lips of the said lugs will be properly spaced upon the tie. Thereafter, the removable locking elements are arranged in their respective pockets, the bolt being depressed against the tension of the springs until the shoulders of the locking elements are arranged upon the shoulders of the pockets, whereupon the bolts will be brought to proper alignment with the slots 7 which form the keepers for the said bolts, and the locking elements, it will be noted, cannot be accidentally removed from the tie without the employment of a suitable instrument therefor.

From the foregoing description, it is thought, the simplicity and advantages of the construction, will be apparent without further detailed description.

It may, however, be necessary to state, that the openings 20 are normally closed by

removable plugs, so that dirt or other foreign matter cannot enter therein.

Having thus described the invention, what I claim is:

1. A metallic tie having a rail engaging lug integrally formed therewith and having a pocket disposed adjacent to the lug, one of the end walls provided by the pocket being beveled, the opposite wall being slotted, a removable rail engaging element, designed to be received in the pocket, and having an inclined end to engage with the beveled end wall of the pocket, a spring pressed latch bolt upon the said element designed to be received in the slot in the opposite end of the pocket, and means, operative exteriorly of the element for actuating the bolt to bring the same to an unlocking position to permit of the separation of the element from the tie.

2. A metallic tie having a rail engaging lug integrally formed therewith and having a pocket disposed adjacent to the lug, one of the end walls provided by the pocket being beveled, the opposite end wall being slotted, a removable rail engaging element designed to be received in the pocket, and having an inclined end to engage with the beveled end wall of the pocket, and a spring pressed latch bolt upon the said element designed to be received in the slot in the opposite end of the pocket.

3. A metal tie having a rail engaging lug integrally formed therewith and having a rectangular pocket disposed adjacent said lug, the wall of the pocket adjacent the lug being beveled inwardly, the opposite wall of the pocket having a slot, the side walls provided by the pocket being stepped to form a shoulder at the upper edges thereof, a removable rail engaging element including a body portion designed to rest upon the shoulders and having a rail engaging lip, said body having a central reduced portion designed to be engaged in the pocket proper, and having one of its ends beveled to co-engage with the beveled end wall of the pocket, a spring pressed bolt carried by the rail engaging member and designed to be received in the referred to slot in the outer end wall of the pocket.

In testimony whereof I affix my signature.

WILLIAM R. DOUGHTY.
